UNITED STATES PATENT OFFICE.

JACOB S. SHERMAN, OF STAUNTON, ILLINOIS.

MINER'S LAMP.

1,167,942.

Specification of Letters Patent. Patented Jan. 11, 1916.

Application filed September 12, 1914. Serial No. 861,438.

To all whom it may concern:

Be it known that I, JACOB S. SHERMAN, a citizen of the United States, residing at Staunton, Illinois, have invented a certain 5 new and useful Improvement in Miners' Lamps, of which the following is a full, clear, and exact description, such as will enable others skilled in the art to which it appertains to make and use the same, reference being had to the accompanying drawings, forming part of this specification, in which—

Figure 1 is a side elevational view of a lamp of my improved construction. Fig. 2 15 is a vertical section taken through the center of the carbide container forming a part of my improved lamp.

My invention relates generally to lamps and more particularly to miners' lamps 20 wherein carbide and water are utilized for producing acetylene gas.

The principal object of my invention is to provide an improved form of carbide container for miners' acetylene lamps and which 25 container is provided with one or more annular ribs on its lower portion, which ribs not only strengthen the container, but provide means whereby the miner or user of the lamp can readily grip the container when 30 the same is detached from the water reservoir of the lamp, and which ribs also provide hammering surfaces which are used when the waste or softened carbide is discharged from the container.

35 In miners' acetylene lamps the action of the water on the carbide in producing acetylene gas creates a certain degree of heat, and thus the carbide container becomes too hot to be easily handled by an operator 40 when said container is unscrewed from the water reservoir and by providing one or more annular ribs, the outer surfaces of which are milled, the operator can obtain sufficient grip on the container to unscrew 45 the same from the water reservoir even while said container is comparatively hot.

With the foregoing and other objects in view, my invention consists in certain novel features of construction and arrangement 50 of parts, herein more fully described and claimed.

Referring by numerals to the accompanying drawings, 1 designates a container for water and which container forms the upper 55 portion of a miner's lamp of ordinary construction. Screw seated on the lower end

of this water container or reservoir is a cup 2, preferably pressed or spun from suitable sheet metal, which cup forms the carbide container of the lamp. Formed on said cup 60 near the lower end thereof is an outwardly projecting annular rib or bead 3, the outer surface of which is milled or corrugated as designated by 4, and formed in the body of the cup a short distance above this lower 65 rib or bead is a second outwardly projecting rib or bead 5, the outer surface of which is milled or corrugated as designated by 6. The upper portion of the wall of the cup or container is contracted as designated by 7 70 and this contracted upper end is pressed to form a thread which is adapted to engage in a corresponding thread in the lower portion of the water container 1. As hereinbefore stated, the carbide cup becomes heated as a result of the water attacking the carbide in said cup, and under such conditions it is a comparatively hard matter for 75 an operator to unscrew the carbide cup by grasping the smooth outer surface of said cup, but where said cup is provided with one or more outwardly projecting ribs or beads, the outer surfaces of which are roughened, said cup may be readily grasped and unscrewed from the water reservoir and 80 which action takes place when it becomes necessary to refill or exchange the carbide 85 cups.

In removing the waste or spent carbide from the carbide cups of miners' lamps it is 90 usually the practice to invert the cup after the same has been removed from the water reservoir, and to strike said cup against a solid object, and where such action takes place with cups of ordinary construction, 95 the same are bent and indented, but by providing one or more annular ribs or beads on said cup, the same is reinforced and hammering surfaces are formed which tend to prevent the cup from being bent or indented 100 when the same is tapped against an object to remove the waste carbide.

A carbide cup of my improved construction is comparatively simple, can be easily and cheaply manufactured, and is adapted 105 for practically all forms of miners' acetylene lamps.

It will be readily understood that minor changes in the size, form and construction of the various parts of my improved carbide cup can be made and substituted for those herein shown and described, without 110

departing from the spirit of my invention, the scope of which is set forth in the appended claim.

I claim:

As a new article of manufacture, a miner's lamp carbid cup formed from a single piece of sheet metal and having a flat bottom, a vertically disposed circular wall extending upwardly from said bottom, an outwardly projecting combined hammering and gripping bead pressed from the metal forming said wall at the point where the same unites with the bottom, an outwardly projecting bead pressed from the metal in the wall at a

point a substantial distance above the combined hammering and gripping bead, the outer faces of both of said beads being milled and the upper end of said vertical wall being contracted and having a thread pressed therein.

In testimony whereof I hereunto affix my signature in the presence of two witnesses, this 10th day of September, 1914.

JACOB S. SHERMAN.
